UNITED STATES PATENT OFFICE.

EDWIN GILBERT, OF GEORGETOWN, CONNECTICUT.

WIRE-NETTING MACHINE.

SPECIFICATION forming part of Letters Patent No. 341,230, dated May 4, 1886.

Application filed March 11, 1886. Serial No. 194,896. (No model.)

To all whom it may concern:

Be it known that I, EDWIN GILBERT, of Georgetown, in the county of Fairfield and State of Connecticut, have invented a certain 5 new and useful Improvement in Wire-Netting Machines, of which the following is a specification.

My invention relates to the class of machines represented in Letters Patent No. 310,254, 10 granted January 6, 1885, to Hiram Combs. Machines of this class are employed in making wire-netting having hexagonal or other polygonal meshes, which are formed by twisting each wire alternately with the wires on 15 the opposite sides thereof and deflecting it between the points of twisting. In such machines are employed a line or row of upper and lower spindles having sectional upper and lower journals and pinions which are divided 20 axially, half of each journal and pinion being formed integral with the spindle, and the other half being made separate from the spindle, but operating in connection therewith to produce the netting. The journals are fitted to 25 bearings which are formed in the meeting edges of slides, each slide containing semi-circular recesses or notches, which form half-circular bearings, and, as described in the aforesaid Letters Patent, these slides, or one of them, 30 has a reciprocating motion which is sufficient to bring the half journal and pinion portions pertaining to each spindle into coincidence with the half journal and pinion of the spindle adjacent thereto. A wire is conducted through 35 each portion or half of the upper journals, and by the shifting of the slides in which the bearings of the journals are formed and the rotation of the journals by racks engaging with the pinions the wires will be properly 40 intertwined, as is described in the aforesaid patent.

In the machines of this class as heretofore constructed one wire of each pair is taken through the half portions of the journals and 45 bearings which are separate from the spindles, and the other wire of each pair is taken from a spool or bobbin, or from a cop-case which is held between the oppositely-arranged spindles of a pair. When the second wire has 50 been taken from a spool or bobbin, it has been necessary to provide a radial opening or hole in the upper spindle, in order to conduct the

wire to the hole or perforation which is provided therein for the wire. When the wire is taken from a cop contained within a cop-case, the spindle through which the wire is conducted is offset and provided with an outside guide for the wire. The spindle being thus offset has not been properly balanced, and hence when the wire has been taken from 60 a cop in a cop-case it has not been possible to drive the spindles as fast as is desirable for economical working.

The object of my invention is to enable cop-cases to be used with spindles which are properly balanced and can be rotated at a high speed.

To this end the invention consists in the combination, with upper and lower spindles constructed with sectional journals and pinions, one spindle of each pair having a direct passage through it from end to end, of cop-cases between the pairs of spindles for containing cops, from which the wire is conducted through the said direct passages in the spindles.

In the combination above described one spindle of each pair is preferably constructed with a socket containing a spring, the other spindle of the pair having a socket or pivot-seat, and the cop-case has pivots or projections for engaging said sockets. The cop-case may then be placed in position by inserting the pivot or projection into the socket in which is the spring, and the spring will yield to enable the cop-case to be moved laterally to bring it in line with the spindles, and by its resilience will hold both pivots thereof in engagement with the spindles.

The above features of construction are included in my invention.

In the accompanying drawings I have only represented such parts of a machine of the kind above described as are necessary to illustrate my invention.

Figure 1 is a transverse section of the upper and lower slides and racks and upper and lower spindles, with an interposed cop-case arranged between them and journaled in said slides, and adapted to be rotated by said racks; 100 also including portions of the framing of the machines and rollers by which the completed netting is taken up; and Fig. 2 is a vertical section, upon a larger scale, of the upper and

lower slides and racks and the two spindles, with an interposed cop-case and cop, a portion of the cop and case being broken away to reduce the vertical dimension of the drawings.

5 Similar letters of reference designate corresponding parts in both figures.

A designates portions of the frame-work of the machine, which may be of any suitable construction, and B B designate the rollers by 10 which the completed netting is taken up after being made.

C C' designate upper and lower spindles, a number of which will be arranged in line widthwise of the machine, and D' designates a 15 cop case, which may be of sheet metal or other material, and which is arranged between and engaged with the two spindles and contains a coil or cop of wire, D'. The upper and lower spindles, C C', each comprise an integral half 20 portion of a journal, c, and a half portion of a pinion, c'. Made separate from but operating with such half journal and pinion portions are other half-journal and half-pinion portions, c* c*, which complete the cylindric journals 25 and pinions of the upper and lower spindle.

E E' designate upper and lower pairs of slides, which have formed in their meeting edges bearings which receive the upper and lower journals, c c*, and between the slides of 30 each pair are racks F F', which engage with the pinions c' c'* and impart rotary motion to them and to the spindles C C'.

The slides and racks E F E' F' may be reciprocated by mechanism such as is described 35 in the aforesaid Letters Patent to Combs, or by any other suitable mechanism. One wire, s, of each pair passes upward through perforations in the journal portions c*, which are separate from the spindles, and the other 40 wire, s', is taken from the cop D' within the cop-case, and is carried directly through a perforation or hole, d, which extends directly through the upper spindle, C, from end to end thereof, and above said upper spindle the wire 45 s' is combined or intertwined with the wire s, as will be readily understood from the aforesaid patent.

By the employment of the cop-case D, which is engaged with upper and lower spindles, as 50 described, and by the construction of the spin-

dle C with a hole or perforation, d, extending centrally and directly through it from end to end thereof, I am enabled to feed the wire s' directly through the spindle C, and to employ a spindle which is perfectly balanced, without 55 the necessity of passing the wire s' radially into the said upper spindle to meet the hole or perforation d, extending through the same, as is done in the Letters Patent above referred to.

In order to provide for the ready engagement and disengagement of the cop-case D with and from the spindles, I form in one spindle (in this instance the lower one, C') a socket, e, of considerable length, and which contains a spring, e', and I form in the upper spindle a 60 conical socket, e''. The cop-case D is provided at opposite ends with pivots or projections f, f', and it will be readily understood that by first introducing the pivot or projection f into the socket e and pressing it downward so as 65 to compress the spring e', the upper pivot, f', may be moved laterally opposite the upper spindle, C, and by the resilience of the spring e' the cop-case will be raised, so as to press the pivot f' into the seat or socket e''. 70

What I claim as my invention, and desire 75 to secure by Letters Patent, is—

1. The combination, with upper and lower spindles arranged in pairs and constructed with sectional journals and pinions, as described, one spindle of each pair having a direct passage through it from end to end, of 80 cop-cases between the pairs of spindles for containing cops, from which the wire is conducted through the said direct passages in the 85 spindles, substantially as herein described.

2. The combination, with upper and lower spindles arranged in pairs and constructed with sectional journals and pinions, as described, one spindle of each pair having a socket cop- 90 containing a spring and the other having a socket, of cop-cases having at the ends pivots or projections, before one of which the spring will yield, to enable the other pivot or projection to be entered into the socket in the opposite 95 spindle, substantially as herein described.

EDWIN GILBERT.
